UNITED STATES PATENT OFFICE

170,800

SHIRT

Ray F. Greer, San Diego, Calif.

Application May 25, 1953, Serial No. 25,184

Term of patent 3½ years

(Cl. D3—25)

To all whom it may concern:

Be it known that I, Ray F. Greer, residing at San Diego, county of San Diego, and State of California, have invented a new, original, and ornamental Design for Shirts, of which the following is a specification, reference being had to the accompanying drawing, forming a part hereof.

Fig. 2 is a rear view thereof.

I claim:

The ornamental design for a shirt, as shown.

RAY F. GREER.
